UNITED STATES PATENT OFFICE

BRUCE M. STANNARD, OF BINGHAMTON, NEW YORK, ASSIGNOR TO THE BREWER-TITCHENER CORPORATION, OF CORTLAND, NEW YORK, A CORPORATION OF NEW YORK

FOLDING CHAIR

Application filed August 8, 1928. Serial No. 298,170.

The present invention relates to collapsible chairs provided with a back member and more particularly of the reversibly folding type adapted to be compactly stacked and stored away when not in use. An object is to provide for a metal chair of this character which while comparatively light, shall be sufficiently cross-braced and of such rigid construction as to support comparatively heavy body loads without undue side-sway effects and otherwise provide for a relatively high degree of stability. A further object consists in improved constructive features which will facilitate convenient collapse of all the chair members into flat aligned relation and admit of readily setting up the chair for use. Embodied herein are further details of structure, designed to accomplish the foregoing and related purposes, all of which will be more explicitly set forth hereinafter.

Reference is had to the annexed one sheet of drawings which are illustrative of a specific embodiment of my invention, like characters of reference indicate like parts, and in which drawings:

Fig. 1 is a front elevation of said folding chair as it appears in its set up or open position while Fig. 2 is a side view thereof indicating in partial dotted outline, the pivoted mode of reversely collapsing my chair back member.

Fig. 3 represents a top or plan view of Fig. 1.

Fig. 4 shows an elevational side view of my chair as it appears when fully collapsed, and Fig. 5 a front view thereof. Fig. 4A represents a fragmental rung detail as taken along the section line 4A—4A of Fig. 4.

Fig. 6 is an enlarged detail of the hinge structure used between the seat and back member of my folding chair while Fig. 7 is a plan or top view of said hinge detail.

Referring now to said drawings, my chair essentially comprises a pair of parallelly spaced front legs A¹ and A^{1'} of the metal type preferably made up of cross-sectionally dished shape straps; this chair also comprises a similar pair of rear legs designated as B¹ and B^{1'}, that are disposed in an outwardly straddled relation and respectively pivoted at

B² intermediate their ends to one of said front leg straps in a collapsible manner. The bottom of this scissor-like leg structure, when opened into set-up position, is intended to rest evenly upon the floor while the oppositely offset upper extremities A² and A^{2'} of said spaced front legs respectively extend beyond the complementary ends of the rear legs as indicated in Figs. 2 and 5. Said complementary rear legs B¹ and B^{1'} may be interconnected through the rung B⁵ and this is reenforced by truss-like lateral brace means preferably embodied in X shaped cross-straps which in the present instance, comprise two component V shaped straps B³ and B^{3'} having their respective noses adjoined at B⁴ with their radially extended leg portions riveted in a substantially central relation to the axis of the respective rear leg strips. The floor contacting leg elements of the last named legs are preferably bent up as shown and may further be tied together by circular rung means such as B⁵ of which the respective ends may be riveted in place in the usual fashion.

The pair of front legs A¹ and A^{1'} are preferably disposed in an outwardly straddled relation with respect to the described rear leg structure; in collapsed position, all of said leg members are intended to fall into substantial alignment as represented in Fig. 4. Said pair of front legs are further interconnected by offset rung means such as A³ and A^{3'}, and in order to allow of the cited aligned folding, the latter rungs are each provided with a spanning element preferably of the cross-sectionally dished metal strap type having upturned flattened end portions that are respectively riveted to and interlockingly received by separate flattened indents or notches A⁴ as formed in each of the slightly dished edges of the front legs in the manner indicated in Fig. 4A. As clearly shown in Figs. 2 and 4, my improved rung members are oppositely disposed relative to the respective front leg edges and by their use, the pair of rear legs may readily be collapsed within the confines of the pair of front legs without need of cutting away said rear legs in order to avoid interference with either of said cross rungs A³ or A^{3'}. Referring further to the disposi-

tion given to the aforesaid cross-braces, they are so arranged as to obviate interference when folding the pivoted leg pairs into complete alignment.

5 Across the free upper ends of the rear legs **B¹** and **B^{1'}**, the pivots **C¹** and **C^{1'}** swivelly carry the forward portion of the seat **C**. The offset upper front leg extremities **A²** and **A^{2'}** are each likewise provided with complementary pivots such as **D⁶** between which there 10 is swivelly mounted the back **D** as shown. The uppermost unfolded edge of said back member is preferably rounded off in flanged semi-circular fashion while the corresponding 15 opposite straight-lined edge portion **D¹** is preferably provided with fairly sharp rounded flange corner regions **D²** and **D^{2'}**, respectively adjoined to said semi-circular portion by the pendant side flange portions 20 **D³** and **D^{3'}** which in turn serve to mount the respective back pivots. Said back **D** is 25 preferably given approximately the same width dimension as the seat and may be stamped out of comparatively light gauge sheet metal with the continuous circumscribing edge flange turned in a normal pendant relation to the back plate as is cross-sectionally indicated by **D^{1'}** in Fig. 6. If desired, 30 said back member may also be equipt with a sunken endless groove **D⁸** into which may be secured and trimmed the margin of the back upholstery fabric **D⁹**. The seat member **C** may be cushioned in a like manner and this is generally indicated by the upholstery 35 reference numeral **C²**.

The rear edge **C³** of the unfolded seat may be hingedly connected to the adjacent bottom back edge **D¹** by an elongated pintle **C⁶** extending between the respective corner regions 40 of said hinged edges in the fashion shown in Figs. 1 and 2. To this end, said pendant flange portion **D^{1'}** is preferably slotted at **D⁴** and **D^{4'}** in spaced relation as respectively disposed closely adjacent to the back corner regions **D²** and **D^{2'}**. A perforated hinge strap **D⁵** projects outwardly from said edge **D^{1'}** in overhanging relation beyond each of said slots and the respective opposite strap ends **D^{5'}** may be riveted or otherwise secured 50 to said inturned back flanges and each such strap end may be given an opposed offset shape adapted to snugly nest into the interior contour of the pendant back edges in accordance with Fig. 7 so as to afford a neat and 55 inconspicuous trim for said hinge element. As shown in Fig. 1, these straps are preferably extended upwardly to the respective front leg pivots **D⁶** and may be riveted thereto for back reenforcing purposes.

60 As will be seen from Fig. 3, the seat **C** is preferably given a practically square contour having a substantially straight inturned rear flange edge **C³**, the respective ends of which connect with inturned corner flanges 65 **C⁴** and **C^{4'}** in a manner that closely resembles

the previously described corresponding flange structure of my back member. Secured to each of the respective seat corner flanges, is a unitary sheet-metal bracket member that comprises a strap portion **C⁵** having one of its ends adapted to overhang the rear seat edge **C³** and mount the pintle rod **C⁶** that pivotally engages the aforesaid pair of back hinge straps **D⁵** and serves as a finger guard. These complementary seat hinge straps are 70 preferably so proportioned that the rear seat edge **C³** and the adjacent back edge **D^{1'}** will lie in substantial alignment when the chair is wholly collapsible as in Fig. 4.

The fixed end of each complementary bracket strap **C⁵** is respectively riveted or otherwise secured to the exterior of the rounded seat edge flanges **C⁴** and **C^{4'}** as shown in Figs. 3 and 7. It will further be observed that there is integrally formed with each such bracket an outwardly projecting stop lug **C⁷** equipt with a V-shaped notched end **C^{7'}** respectively adapted to grippingly receive therebetween the rear edge of one front leg strap such as **A¹** or **A^{1'}**, thus providing 80 for an additional supplementary leg tie adjacent to the rear seat portion as disposed intermediate the front leg pivots **B²** and **D⁶** which serves to impart augmented lateral 85 rigidity to my chair whenever it is brought into fully unfolded position. Collapsible steel chairs of the conventional type tend to wear or otherwise become loose in the pivot joints and accordingly is likely to result in undue side sway when the chair is 90 placed under seat load. The provision for 95 said complementary hook means as used in conjunction with the aforesaid brace means **B²**, serves to tie together the respective spaced cross-leg members of my opened chair into 100 a unitary structure that is amply braced against lateral tilt effects.

For convenience of manipulation, the bottom inturned flange edge **D^{1'}** of my back member may be provided with a handle **D⁷** which may comprise a U shaped strap-like grip element adapted to extend outwardly in offset alignment with the plane of the back as indicated in Fig. 6. In unfolded chair position, said hand grip **D⁷** is positioned downwardly with respect to the rear edge seat edge **C³** in the manner shown by full lines in Fig. 2; by the raising of said grip, the back may be swung through the intermediate dotted position of Fig. 2, which in turn throws upside down the semi-circular top edge of the back until it finally reaches the fully inverted or reversed relation that is represented in Figs. 4 and 5, where the hand grip **D⁷** is now brought above the top of the rear seat edge **C³** in convenient location for readily unfolding the chair.

All of my chair members are pivotally linked together to provide for a positive relative folding movement therebetween, and 130

assuming the folded chair legs to be resting upon the floor as indicated in Fig. 4, said handle member then being raised clear of the aligned uppermost back and seat members, it may readily be given a simultaneous rearward and downward jerk adapted to thrust the seat forwardly about the complementary back pivots D^e , whereupon the component linked chair members may again be guided and swung through the intermediate relation shown by dotted lines in Fig. 2 and ultimately reach the erected position represented in full lines, the handle D^f now being placed into its lowermost position and made ready for convenient lifting and inverting the member D back into collapsed position for stacking purposes.

When the chair is fully opened and subjected to seat load, the complementary stop hook members C'' press forwardly against and snugly interlock with the rear edge of the respective front legs A^1 and $A^{1'}$, which in turn not only prevents further spreading apart of the respective crossed leg members about their respective pivots B^2 but also imparts augmented lateral rigidity to the rear portion of my erected seat. As an additional precaution, it is preferred to have either the inturned rear edge portion of the seat or the lower face of the flap stop lug C^r so arranged as to come into substantial abutment with and rest upon the uppermost edge of said offset rung A^3 as indicated in Fig. 2, thus further providing against side-sway on part of the chair under heavy seat load.

Although certain specific embodiments and shapes of metal chair members have herein been set forth, I do not wish to be limited to the cited arrangement or form of parts, since various changes may be resorted to, all without departing from the spirit and scope of my invention, heretofore described and more specifically pointed out in the appended claims.

45 I claim:

1. A folding chair having the elements thereof positively linked together for co-ordinated movement, said chair comprising a pair of rear leg straps, truss-like cross-brace means disposed between and adapted to fixedly hold the respective leg edges in spaced relation, a front leg pivoted to each of said rear legs in scissor-like fashion, said front legs being disposed astride the respective outermost side faces of said rear leg straps and extended beyond the respective upper rear leg extremities, rung means interconnecting said pair of front legs, said rear leg structure together with said brace means being adapted to fold into collapsed alignment within the confines of said pair of front legs and to unfold into open crossed leg position, a back member pivotally mounted between the pair of front leg extensions, a seat member pivotally mounted between the upper end portions

of the pair of rear legs, stop means overhung outwardly from each of the seat sides and respectively adapted to open seat position to interlockingly grasp the rearward edge of its adjacent front leg strap, and hinge means pivotally interconnecting the back to said seat, said means allowing of swinging the seat member about the aforesaid seat pivots and of swinging the adjoined back member about its front leg extension pivots into a reversed folded relation upon said seat and into substantial alignment with the collapsed leg structure.

2. A folding chair comprising a pair of rear legs, cross brace means disposed between and serving to fixedly hold said legs in spaced relation, a front leg strap pivoted to each of the rear legs and extending beyond the respective upper extremities of the last named legs, said front legs being interconnected by rung means and the rear leg structure together with said brace means being adapted to fold into collapsed alignment within the confines of the pair of front legs and to unfold into crossed leg position, a back member pivotally mounted between the pair of front leg extensions, a seat member pivotally carried between the upper end portions of said pair of rear legs, hinge means pivotally connecting the back to said seat, said means being adapted to allow of swinging the seat and back members about their respective pivots from substantial alignment with the collapsed leg structure into open position, and a pair of spaced unitary brackets associated with the rearward seat portion, each such bracket including a pivot support element adapted to have the back hinged thereto and also a stop element respectively disposed to overhang opposite seat sides and in open seat position adapted to interlock with the rearward edge of the adjacent front leg strap.

3. A folding chair comprising a pair of rear legs fixedly held in spaced relation by interconnecting means, a front leg strap pivoted to each of the rear legs and extending beyond the respective upper extremities of the last named legs, rung means disposed to interconnect the pair of front legs intermediate the extension ends thereof and their respective rear leg pivots and which rear leg structure as a whole is adapted to fold into collapsed alignment within the confines of the pair of front legs and to unfold into open crossed leg position, a back member pivotally mounted between the pair of front leg extensions, a seat member pivotally carried between the upper end portions of said pair of rear legs which pivots are adjoined to the forward portion of the unfolded seat while the rear seat portion in open position is adapted to rest upon said rung means, hinge means pivoting the back to said seat, and stop lug means disposed outwardly from each of the opposite seat sides in close proximity to the respective

- rung ends and respectively adapted to interlock with one of the rear edges of the complementary front leg straps whenever said rear seat portion rests upon said rung.
4. A folding all-metal chair comprising a pair of rear legs fixedly held in spaced relation by interconnecting means, a front leg strap pivoted to each rear leg and extending beyond the respective upper extremities of the last named legs, said front legs being interconnected by rung means and the rear leg structure as a whole being adapted to fold into collapsed alignment within the confines of the pair of front legs and to unfold into open crossed leg position, a sheet metal seat member pivotally mounted between the upper end portions of said pair of rear legs, said seat being provided with a pendant circumscribing flange including complementary rounded corner elements, a hinge strap secured to the exterior of each of the aforesaid seat corner elements, a sheet metal back member pivotally mounted between the pair of front leg extensions, the perimeter of said back being likewise provided with a pendant flange of which one portion is kept substantially straight and provided with a pair of spaced slots, a hinge strap disposed through each of said slots and respectively adapted to cooperate with the aforesaid seat straps and hinge said seat to the back member.
5. A folding all-metal chair comprising a pair of rear legs held in aligned spaced relation by interconnecting means, a front leg strap pivoted to each rear leg and extending beyond the respective upper extremities of the last named legs, said front legs being interconnected by rung means and the rear leg structure as a whole being adapted to fold into collapsed aligned leg position and to unfold into open crossed leg position, a sheet metal seat member pivotally mounted between the upper end portions of said pair of rear legs, said seat being provided with a circumscribing pendant flange including complementary rounded corner elements, a unitary bracket associated with each corner element, each such bracket comprising an integrally formed hinge strap means together with a stop means respectively adapted to interlock with its contiguous front leg strap edge and limit the unfolding of said crossed leg members, a sheet metal back member pivotally mounted between the pair of front leg extensions, the perimeter of said back being likewise provided with a pendant marginal flange to which is adjoined spaced hinge strap means respectively adapted to cooperate with the aforesaid seat hinge straps, and pintle means pivotally interconnecting the said seat hinge straps with the back hinge strap means.
6. A folding chair comprising legs, a seat, a back having a flanged edge to which the legs are pivoted, and a combined reinforcing
- and hinge strap associated with said flanged edge, said strap being hinged to the seat and also serving to reinforce the pivotal connection for the legs.
- In testimony whereof, I have herewith set 70 my hand this 6th day of August, 1928.
